UNITED STATES PATENT OFFICE.

GEORGE SMILEY, OF KALAMAZOO, MICHIGAN.

WAGON.

SPECIFICATION forming part of Letters Patent No. 367,247, dated July 26, 1887.

Application filed October 12, 1886. Serial No. 216,002. (No model.)

To all whom it may concern:

Be it known that I, GEORGE SMILEY, a citizen of the United States, residing at Kalamazoo, county of Kalamazoo, State of Michigan, 5 have invented a new and useful Wagon, of which the following is a specification.

This invention relates to that class of wagons which have two reaches obliquely crossing each other between the axles. It has for its 10 object certain improvements in connection with such reaches.

In the drawings forming a part of this specification, Figure 1 is a side elevation with the wagon-wheels on one side removed. Fig. 2 is 15 a plan view.

Referring to the lettered parts of the drawings, B B are the crossed reaches. They are pivotally connected at the ends to the axles C by means of pivotal bolts b, passed through 20 straps secured to the ends of the reaches and through a lug, c, integral with one side of the rear end of the axle-skein.

The bolster-supports D are a continuation of the pivotal straps of the reaches.

Referring to Fig. 1, the bar D is secured to the under side of the reach B at the ends, from thence passes beneath the axle C, then well forward and upward, back over the axle in a circle or curve, Fig. 2, but horizontally straight 25 on top, Fig. 1, from thence downward onto the reach, and forward to the point of pivoting at b. Of course the bolsters E are held by the ordinary king-bolt, (not here shown,) so as to allow the axles to turn, as indicated by 30 dotted lines in Fig. 2, when turning out of a straight course, during which action the bars

D form a support for the bolsters E. Only one bolster is shown in Fig. 2, one end of which is broken to show the hinging-eye c beneath.

The advantages of having both front and 40 rear axles turn is well understood without dwelling upon that point.

This plan of constructing a reach-coupling and bolster-support from a single strip of iron makes a strong attachment, well braced, and 45 safely supports the ends of the bolsters, and the hinging-eye, being integral with the skein or collar upon which the wheel revolves, makes a strong connection without weakening the axles. However, the reaches and bolster-supports may be attached by pivot direct to 50 the axles, if preferred.

Having thus described my invention, what I claim as new, and desire to secure by Letters Patent, is—

1. The combination of the reaches, the skeins having the hinging-lugs, and the bolster-supports secured to the forward end of the reaches and hinged to said lugs, substantially as set forth.

2. In a vehicle, the combination of the axles, crossed reaches, and the bolster-supports pivotally attaching the reaches to the axles, and having the upper curved flat portion, substantially as set forth.

In testimony of the foregoing I have hereunto subscribed my name in presence of two witnesses.

GEORGE SMILEY.
